(57) **CLAIM**

The ornamental design for lid for container, as shown and described.

DESCRIPTION

FIG. 1 is a perspective view of a first embodiment of a plastic lid for use with container;

FIG. 2 is a top view of FIG. 1;

FIG. 3 is a bottom view of FIG. 1;

FIG. 4 is a front view of FIG. 1;

FIG. 5 is a rear view of FIG. 1;

FIG. 6 is a right side view of FIG. 1; and

FIG. 7 is a left side view of FIG. 1;

FIG. 8 is a perspective view of a second embodiment of a plastic lid for use with a container;

FIG. 9 is a top view of FIG. 8;

FIG. 10 is a bottom view of FIG. 8;

FIG. 11 is a front view of FIG. 8;

FIG. 12 is a rear view of FIG. 8;

FIG. 13 is a right side view of FIG. 8; and

FIG. 14 is a left side view of FIG. 8;

FIG. 15 is a perspective view of a third embodiment of a plastic lid for use with a container;
FIG. 16 is a top view of FIG. 15;
FIG. 17 is a bottom view of FIG. 15;
FIG. 18 is a front view of FIG. 15;
FIG. 19 is a rear view of FIG. 15;
FIG. 20 is a right side view of FIG. 15; and
FIG. 21 is a left side view of FIG. 15;
FIG. 22 is a perspective view of a fourth embodiment of a plastic lid for use with a container;
FIG. 23 is a top view of FIG. 22;
FIG. 24 is a bottom view of FIG. 22;
FIG. 25 is a front view of FIG. 22;
FIG. 26 is a rear view of FIG. 22;

FIG. 27 is a right side view of FIG. 22; and
FIG. 28 is a left side view of FIG. 22;
FIG. 29 is a perspective view of a fifth embodiment of a plastic lid for use with a container;
FIG. 30 is a top view of FIG. 29;
FIG. 31 is a bottom view of FIG. 29;
FIG. 32 is a front view of FIG. 29;
FIG. 33 is a rear view of FIG. 29;
FIG. 34 is a right side view of FIG. 29; and,
FIG. 35 is a left side view of FIG. 29.
The broken lines in the drawing views are included for the purpose of illustrating portions that form no part of the claimed design.
